No. 858,469.

PATENTED JULY 2, 1907.

W. J. RICHARDS.
FLUID PRESSURE SYSTEM.
APPLICATION FILED OCT. 6, 1904.

UNITED STATES PATENT OFFICE.

WALTER J. RICHARDS, OF MILWAUKEE, WISCONSIN.

FLUID-PRESSURE SYSTEM.

No. 858,469.

Specification of Letters Patent.

Patented July 2, 1907.

Application filed October 6, 1904. Serial No. 227,511.

To all whom it may concern:

Be it known that I, WALTER J. RICHARDS, a citizen of the United States, residing at Milwaukee, in the county of Milwaukee and State of Wisconsin, have invented a certain new and useful Improvement in Fluid-Pressure Systems, of which the following is a full, clear, concise, and exact description, reference being had to the accompanying drawings, forming a part of this specification.

10 My invention relates to electrically driven fluid pumps, and particularly to the use of alternating currents for the purpose of supplying the necessary energy to the motor mains.

In a general way, the present invention is similar to an invention disclosed in my co-pending application Serial No. 164,085, filed July 2, 1903, in which, however, the motor is adapted for use in conjunction with a supply of direct current.

In accordance with my present invention, I provide a pressure system supplied by a pump or compressor, the operation of the compressor being controlled in accordance with variations in the pressure in the system, whereby the pressure within the system is maintained at or near a given constant pressure.

25 My invention provides means whereby the supply of current to the motor at starting is controlled in such a way that the motor will not be subjected to an undue rush of current, which would either burn out the windings or require the motor to be of uneconomical design.

30 In addition to the provision of means for limiting the supply of current to the motor at starting, independently of the load on the motor, this invention provides also a means for permitting the motor to start under practically no load conditions, the load being thrown 35 upon the motor only after it has attained substantially its full normal speed.

The invention is diagrammatically illustrated in the accompanying drawing.

At 10 I have illustrated a storage reservoir or tank, from which the supply pipe 11 leads to the devices which, in this instance, are intended to be operated by compressed air. The tank is supplied with compressed air by means of the compressor 12, which is driven by means of an alternating current motor 13. A 40 controlling switch 14 is connected by means of the pipe 15 with the reservoir 10 and serves to control the operation of the motor in accordance with variations in the pressure system. This switching device consists essentially of a bent tube 16, like that of a Bourdon pressure gage, which is connected by means of the link 17 with a switch arm 18, this switch arm moving between the contacts 19 and 20. At A I have shown a switching device, which, in mechanical construction, may be like that shown in my co-pending application, Serial No. 50 152,165, filed April 11, 1903.

In the diagram I have shown the insulated contacts

21, 22, 23 and 24, the contacts 21 and 22 being electrically connected by means of the connector clip 25, when brought into engagement therewith, and the contacts 23 and 24 being connected by means of the clip 26, the 60 clips 25 and 26 operating concurrently in accordance with the movements of the core 27. The solenoids 28 and 29 cause the reciprocation of the core 27 either one way or the other, depending upon which solenoid is traversed by an electric current. The operation of this 65 device will hereinafter be more fully explained.

At B is shown a main switch for connecting the apparatus of my invention with the alternating current mains 30, 31 and 32. The compressor comprises a cylinder 33, piston 34, its piston rod 35, the usual discharge valves 36 and 37, and suction valves 38 and 39. The suction valves are provided with downwardly projecting stems 40 and 41, these stems being engaged respectively by the levers 42 and 43, to the free ends of which are attached the cores 44 and 45, movable within 70 the solenoids 46 and 47, respectively. The weight of the cores serves normally to maintain the suction valves unseated, as shown. Upon energization the solenoids cause the upward movement of their associated cores to permit the seating of the associated suction valves. 75 The alternating current motor comprises primary windings 50, 51 and 52, and secondary windings 53, 54 and 55, these windings being star-connected, as shown in the diagram. The association between these windings is of an inductive nature, as is well understood by those 80 skilled in the art, one of the sets of windings being movable with respect to the other. The star-connected resistances 56, 57 and 58 are connected with the outer terminals of the secondary windings of the motor, as shown.

90 At C there is a switching device adapted to control the resistances in their electrical association with the secondary winding of the motor. For the purpose of diagrammatic illustration I have shown a series of insulated contacts, 61 to 68, inclusive, all mounted upon a 95 stationary shaft or support 70. These contacts are given somewhat different inclinations, as shown, contacts 61, 62 and 63 having their outer ends in a lower position than the outer ends of the contact fingers 64, 65 and 66, while the contact fingers 67 and 68 are slightly higher 100 than either of the other sets. A short-circuiting contact plate 71 is supported by means of the insulated and pivoted bars 72 and 73, an auxiliary contact plate 74 being mounted to oscillate with the contact plate 71. The movement of these contact plates is controlled by a 105 solenoid 75, into which the core 76 projects, this core connecting by means of the cord 77 with the contact plate 71. The drawing shows the contact plate 71 slightly above its normal position and in engagement with the contact fingers 61 to 63, inclusive. The upward movement of the contact plate 71 is retarded by the dashpot diagrammatically illustrated at 79.

The operation of these devices may be described as follows:—Assuming the main switch B to be closed and that the pressure in the reservoir 10 has been reduced to its minimum limit, the switch arm 18 is brought into engagement with the contact post 19, thereby closing a circuit which may be traced as follows: from the main 32, through conductor 80, conductor 81, solenoid 28, contact post 19, switch arm 18, conductor 82, conductor 83, conductor 84, to the motor winding 52, to the neutral point, thence through winding 50 and conductor 85 to the main 30. Current flowing through this circuit energizes the coil 28, causing a movement of the core 27 to the left, and electrically connecting the contacts 21 and 22 by means of the clip 25, and the contacts 23 and 24 by means of the clip 26. The movements of this switching device A completes the closure of the primary circuit of the motor, this circuit being traced from the main 30 through conductor 85 and coil 50 to the neutral point; from main 31, through conductor 86, contact 21, connecting clip 25, contact 22, conductor 87 and coil 51 to the neutral point; and from main 32 through conductor 80, contact 24, connecting clip 26, contact 23, conductor 83, conductor 84, and coil 52, to the neutral point. The currents traversing these primary windings induce currents in the secondary coils 53, 54 and 55, the secondary circuit being closed through the resistances 56, 57 and 58. On the initial closure of the switch A the resistances are included directly in the secondary circuit, the switch blade 71 being in its lowest position and out of contact with all of the contact fingers 61 to 66, inclusive. The actuation of the switch A also closes another circuit, which may be traced as follows: from the main 31, through conductor 86, contact 21, connecting clip 25, contact 22, conductor 88, solenoid 75, conductor 83, contact 23, connecting clip 26, contact 24 and conductor 80, to the main 32. The energization of this coil 75 causes an upward attraction of its core 76, whereby the contact plate 71 is drawn slowly upward against the retarding influence of the dashpot 79. The contact plate 71 first engages the three fingers 61, 62 and 63. The inner sections of the resistances are thus short-circuited, cutting down the total resistance in the secondary circuit of the motor. As shown in this diagrammatic figure, the contact fingers are thin and flexible, so that the upward movement of the contact plate is not arrested by engagement with the first three contact fingers. The upward motion is continued, therefore, until engagement is made with the three contact fingers marked 64, 65 and 66. This connection serves to complete the short-circuit of the resistances 56, 57 and 58, whereby the secondary circuit of the motor is completed through circuits of almost no resistance whatever. As is well understood by those skilled in the art, the decrease of the resistance in the secondary circuit not only permits an increase of the flow of current in the secondary circuit but in the primary circuit also, but during the cutting out of the resistance in the secondary circuit the motor is increasing its speed of rotation, whereby the increasing electrical and magnetic reactions within the motor serve to prevent the flow of excessive currents through the motor windings. As the core 76 continues its upward motion, the contact plate 74 is ultimately brought into engagement with the contact fingers 67 and 68, whereby the circuit is closed through the solenoids 46 and 47, thereby causing their energization and

the upward attraction of their cores 44 and 45 respectively, this movement of the cores permitting the suction valves 38 and 39 to seat, thereby throwing the load of the compressor upon the motor and causing the discharge of compressed air into the reservoir 10. It will be noted that during the period in which the resistances are included in the secondary motor circuit and until these resistances are cut out of the circuit, during which period the motor will have attained substantially its full normal speed of rotation, the suction valves are prevented from seating, whereby the motor is brought to speed under practically no load conditions, the air being alternately drawn into the compressor cylinder and expelled therefrom by way of the ports of the suction valves. After the compressor has discharged into the reservoir for a sufficient length of time to bring the pressure to its maximum limit, the switch arm 18 of the governor is brought into electrical connection with the contact 20, whereby a circuit is closed through the solenoid 29, this circuit being traced as follows: from the main 31, to contact 21, connecting clip 25, contact 22, thence by way of the conductor 90 through the coil 29, conductor 91, contact post 20, switch arm 18, conductor 82, contact 23, connecting clip 26, contact 24, and conductor 80, back to the main 32. The energization of this coil 29 causes a movement of the core 27 to the right, thereby breaking the electrical connection between the contacts of the switching device A. This opens the circuits which have heretofore been traced. The weight of the cores 44 and 45 returns their suction valves to their positions as shown in the drawing in which they may not seat themselves upon the operation of the compressor, and the weight of the movable switch members of the switching device C returns the contact plates 71 and 74 to their normal position in which the short-circuits about the resistances 56, 57 and 58 are removed. The apparatus is thus returned to its normal condition, whereupon the decrease of pressure in the system to its minimum limit causes a repetition of the operation already described.

It will be understood that this description and the accompanying drawing show only in outline the actual mechanical structures which in practice would be employed to carry out my invention. Furthermore, I do not wish to be limited to the precise construction set forth, but

What I claim as new and desire to secure by Letters Patent is set forth in the following claims.

1. In combination, an alternating current motor, having a primary circuit and a secondary circuit, a resistance normally included in the secondary circuit, slow-acting electromagnetic mechanism adapted upon energization gradually to reduce the resistance in said secondary circuit, a switch for closing the primary circuit, and means associated with said switch for causing the energization of said electromagnetic mechanism upon the closure of the primary circuit.

2. In combination, an alternating current motor, having a primary circuit and a secondary circuit, a resistance normally included in the secondary circuit, slow-acting electromagnetic mechanism adapted upon energization to reduce the resistance in said secondary circuit, a switch for closing the primary circuit, and means for causing the energization of said electromagnetic mechanism upon the closure of the primary circuit.

3. In combination, an alternating current motor, having a primary circuit and a secondary circuit, a resistance normally included in the secondary circuit, electromagnetic mechanism adapted upon energization to reduce the re-

- sistance in said secondary circuit, a retarding device associated with said electromagnetic mechanism, a switch for closing the primary circuit, and means for causing the energization of said electromagnetic mechanism upon the closure of the primary circuit. 5
4. In combination, an alternating current motor, having a primary circuit and a secondary circuit, current-restricting means associated with the secondary circuit of said motor, slow-acting electromagnetic mechanism adapted upon energization to remove the restriction to the flow of current in the secondary circuit of said motor, a switch for closing the primary circuit, and means for causing the energization of said electromagnetic mechanism upon the closure of the primary circuit. 10
- 15 5. In combination, a fluid pump, an alternating current motor for driving said pump, said motor having primary and secondary circuits, slow-acting electromagnetic mechanism adapted upon energization to gradually reduce the resistance of the secondary circuit of the motor, and means for causing the energization of said electromagnetic mechanism upon closure of the primary circuit. 15
- 20 6. In combination, a fluid pump, a pressure system supplied thereby, an alternating current motor for driving said pump, said motor having primary and secondary circuits, a resistance normally included in the secondary circuit, a switch governed by the pressure in the system for controlling the primary circuit of the motor, and automatic means for cutting the resistance out of the secondary circuit of the motor after the closure of the primary circuit. 25
- 30 7. In combination, a fluid pump, a pressure system supplied thereby, an alternating current motor for driving said pump, said motor having primary and secondary circuits, current-restricting means associated with the secondary circuit, a switch governed by the pressure in said system for controlling the primary circuit of the motor, and automatic electromagnetic means associated with said switch for removing the restriction to the flow of current in the secondary motor after the closure of the primary circuit. 35
- 40 8. In combination, a fluid pump, an alternating current motor having primary and secondary circuits, said pump being driven by said motor, a resistance normally included in the secondary circuit, automatic electromagnetic switching mechanism for cutting out the resistance in said secondary circuit, means for retarding the motion of said electromagnetic mechanism, and means for closing the circuit through said electromagnetic mechanism upon the closure of the primary circuit. 45
- 50 9. In combination, a fluid pump, a pressure system supplied thereby, an alternating current motor for driving said pump, said motor having primary and secondary circuits, a switch governed by the pressure in said system for closing the primary circuit of said motor, a resistance included in the secondary circuit of said motor, switching means for cutting the resistance out of said secondary circuit, automatic electromagnetic mechanism for operating said switching means, a retarding device associated with said automatic electromagnetic mechanism, and means associated with the first said switch for closing the circuit through said electromagnetic mechanism upon the closure of the primary circuit. 55
- 60 10. In combination, an alternating current motor, an air compressor driven thereby, a pneumatic pressure system supplied thereby, means controlled by the pressure in said system to close the motor circuit upon a decrease in the pressure in the system to a minimum limit and to open the motor circuit upon an increase in such pressure to a maximum limit, a resistance in the secondary circuit of said motor, a path of high conductivity including a normally open switch connected in shunt of said resistance, electromagnetic means associated with the motor circuit adapted upon energization to close said switch, mechanism serving normally to maintain the valves of said compressor in an open condition, and means for actuating said mechanism to allow closure of said valves when said resistance has been cut out of circuit. 70
- 75 11. In combination, an air compressor, a pneumatic pressure system supplied thereby, an alternating current electric motor for driving said compressor, said motor having primary and secondary circuits, means controlled by the pressure in said system to close the primary circuit of said motor upon a decrease in the pressure in said system to a minimum limit and to open the primary circuit of said motor upon an increase in the pressure in said system to a maximum limit, an automatic rheostat for restricting the starting current in the secondary circuit of said motor, and automatic electromagnetic means adapted for electrical connection with the motor circuit to increase the load on said pump after the lapse of a suitable 80
- the pressure in said system to close the motor circuit upon a decrease in pressure in the system to a minimum limit and to open the motor circuit upon an increase in said pressure to a maximum limit, a resistance in the secondary circuit of the motor, a path of high conductivity including a normally open switch connected in the shunt of said resistance, and slow-acting electromagnetic mechanism included in the motor circuit adapted upon energization to close said switch. 85
- 90 12. In combination, an air compressor, a pneumatic pressure system supplied by said compressor, an alternating current motor for driving said compressor, said motor having primary and secondary windings, means controlled by the pressure in said system to close the motor circuit upon a decrease in the pressure in the system to a minimum limit and to open the motor circuit upon an increase in said pressure to a maximum limit, a resistance in the secondary circuit of the motor, a path of high conductivity including a normally open switch connected in shunt of said resistance, electromagnetic mechanism in a circuit controlled by the motor-controlling switch and adapted upon energization to close said normally open switch connected in shunt of said resistance, a dashpot adapted to control and retard the motion of said electromagnetic mechanism, means for maintaining the suction valves of the compressor in a normally open condition, and electromagnetic means for automatically permitting the closure of said suction valves when said resistance has been cut out of circuit. 95
- 100 13. In combination, an air compressor, an alternating current motor for intermittently driving said compressor, said motor having primary and secondary windings, an automatic rheostat for restricting the flow of current in the secondary winding of said motor independently of the load on said motor, and automatic means for increasing the load on said motor upon the removal of the restriction in the flow of current by said automatic rheostat. 105
- 110 14. In combination, a fluid pump, an alternating current motor for intermittently driving said pump, said motor having primary and secondary circuits, an automatic rheostat for restricting the starting current traversing the secondary circuit of said motor independently of the load on said motor, and automatic electromagnetic means for increasing the load on said compressor upon the removal of the restriction in current flowing in said secondary circuit. 115
- 120 15. In combination, an air compressor, an alternating current electric motor for intermittently driving said compressor, said motor having a primary and a secondary circuit, an automatic rheostat for restricting the starting current in said secondary circuit, and automatic electromagnetic means electrically connected with the motor circuit for increasing the load on said compressor upon the removal of the restriction to the current in the secondary circuit. 125
- 130 16. In combination, a fluid pump, a pressure system supplied thereby, an alternating current motor for driving said pump, said motor having a primary and a secondary circuit, means controlled by the pressure in the system to close the primary circuit upon a decrease in the pressure in said system to a minimum limit and to open said primary circuit upon an increase in said pressure to a maximum limit, an automatic rheostat for restricting the starting current in the secondary circuit of said motor, and automatic electromagnetic mechanism associated with the primary circuit of said motor for increasing the load on said compressor upon the removal of the restriction to the current in the secondary circuit of said motor. 135
- 140 17. In combination, a fluid pump, a pressure system supplied thereby, an alternating current motor for driving said pump, said motor having a primary circuit and a secondary circuit, means controlled by the pressure in said system to close the primary circuit of said motor upon a decrease in the pressure in said system to a minimum limit and to open the primary circuit of said motor upon an increase in the pressure in said system to a maximum limit, an automatic rheostat for restricting the starting current flowing in the secondary circuit of said motor independently of the load on said motor, and automatic electromagnetic means adapted for electrical connection with the motor circuit to increase the load on said pump after the lapse of a suitable 145
- 150 18. In combination, an air compressor, a pneumatic pressure system supplied thereby, an alternating current motor for driving said compressor, said motor having primary and secondary circuits, means controlled by the pressure in said system to close the primary circuit of said motor upon a decrease in the pressure in said system to a minimum limit and to open the primary circuit of said motor upon an increase in the pressure in said system to a maximum limit, an automatic rheostat for restricting the starting current flowing in the secondary circuit of said motor independently of the load on said motor, and automatic electromagnetic means adapted for electrical connection with the motor circuit to increase the load on said pump after the lapse of a suitable 155

- interval after the closure of the primary circuit of said motor.
18. In combination, a fluid pump, a pressure system supplied thereby, an alternating current motor for intermittently driving said pump, said motor having a primary and a secondary circuit, an automatic rheostat for restricting the starting current in the secondary circuit of said motor independently of the load on said motor, and automatic means acting independently of the pressure in said system to increase the load in said motor upon the removal of the restriction in the supply of current by said automatic rheostat. 5
19. In combination, a fluid pump, a pressure system supplied thereby, an alternating current motor for driving said pump, said motor having primary and secondary windings, means controlled by the pressure in said system to close the primary circuit of the motor upon a decrease in the pressure in said system to a minimum limit and to open said motor circuit upon an increase in said pressure to a maximum limit, an automatic rheostat for restricting the starting current supplied to said motor independently of the load on said motor, and automatic electromagnetic controlled means serving normally to maintain the valves of said pump in an inoperative condition but upon the removal of the restriction in the supply of energy to said motor to permit the operation of said valves. 10
20. In combination, an alternating current motor having a secondary circuit, a fluid pump driven thereby, said pump having valves normally maintained in an inoperative condition, a pressure system supplied by said pump, switching means governed by the pressure in said system to control the supply of energy to the motor, means for restricting the flow of current in the secondary circuit of said motor at starting, and electromagnetic means automatically actuated to permit the operation of said valves upon the removal of the restriction to the flow of current in said motor circuit. 15
21. In combination, a fluid pump having suction valves normally maintained in an open condition, an alternating current motor for driving said pump, said motor having a primary and a secondary circuit, a pressure system supplied by said pump, switching means controlled by the pressure in said system to control the primary motor circuit, means for restricting the flow of current in the secondary circuit of the motor at starting, means for automatically permitting the operation of said valves, and means for removing the restriction of the supply of current to said motor after the lapse of a suitable interval after the initial closure of the motor circuit. 20
22. In combination, a fluid pump, an alternating current motor for driving said pump, said motor having primary and secondary circuits, switching means for controlling the supply of current to said motor, means serving normally to prevent the operation of the pump valves, a resistance normally included in the secondary circuit of said motor, slow acting electromagnetic mechanism adapted to short circuit said resistance after the lapse of a suitable interval after the closure of the motor circuit, and electromagnetic mechanism associated with said pump valves and adapted to incapacitate said preventive means after the initial supply of current to said motor. 25
23. In combination, an alternating current electric motor having a primary circuit and a secondary circuit, a fluid pump driven thereby, switching means controlling the circuit through said motor, a resistance normally included in the secondary circuit of the motor, automatic means for gradually disconnecting said resistance from the secondary circuit upon the closure of the primary circuit, means serving normally to prevent the operation of the valves of the compressor, electromagnetic mechanism serving when energized to permit the operation of said valves, and means for causing the energization of said electromagnetic mechanism after said resistance has been cut out of the secondary circuit of the motor. 30
24. In combination, an alternating current motor having a primary circuit and a secondary circuit, an air compressor driven thereby, a pneumatic pressure system supplied by said compressor, switching mechanism governed by the pressure in said system to cause the closure of the primary circuit of said motor upon a decrease in the pressure in said system to a minimum limit and to cause a break in the primary circuit of the motor upon an increase in the pressure in said system to a maximum limit, a slow acting automatic rheostat associated with the secondary circuit of the motor and adapted gradually to short circuit resistances normally included in the secondary motor circuit after the closure of the primary circuit of the motor, means serving normally to maintain an opening in each end of the compressor cylinder, and electromagnetic mechanism energized after said resistances have been cut out of the secondary circuit to cause the closure of the openings in the ends of the compressor cylinder. 35
25. In combination, a fluid pump, a pressure system supplied thereby, an alternating current motor for driving said pump, said motor having primary and secondary circuits, a resistance normally included in the secondary circuit, an electromagnetic switch governed by the pressure in the system for controlling the primary circuit of the motor, and automatic means for cutting the resistance out of the secondary circuit upon the closure of the primary circuit by said electromagnetic mechanism. 40
26. In combination, an alternating current motor, a pump driven thereby, a pneumatic pressure system supplied by said pump, means controlled by the pressure in said system to close the motor circuit upon a decrease in the pressure in the system to a minimum limit and to open the motor circuit upon an increase in the pressure to a maximum limit, a resistance in the secondary circuit of said motor, switching mechanism connected with said resistance, electromagnetic mechanism for controlling said switching mechanism, said electromagnetic mechanism being actuated upon connection of the primary in circuit, valves for said pump, preventative means serving normally to prevent operation of said valves, electromagnetic means controlling said preventative means, and a circuit for said electromagnetic mechanism closed by said switching mechanism after the resistance has been removed from the secondary circuit, whereby said valves become operative. 45
27. In combination, an alternating current motor having primary and secondary circuits, of a pump driven by said motor, an electromagnetic switch controlled by the pressure in the system supplied by said pump for connecting the primary of said motor in circuit, a second electromagnetic switch controlled by said first electromagnetic switch, a resistance normally included in the secondary circuit of the motor, contacts for said second electromagnetic switch connected with said resistance, means for causing successive actuation of said contacts, whereby said resistance is gradually removed from circuit, normally inoperative valves for the pump, electromagnetic mechanism controlling said valves, and a circuit including electromagnetic means adapted to be closed by said second electromagnetic switch to render said valves operative after said resistance has all been removed from circuit. 50
28. In combination, a fluid pump, an alternating current motor for driving said pump, said motor having primary and secondary circuits, switching means for controlling the supply of current to said motor, means serving normally to prevent effective operation of the pump, a resistance normally included in the secondary circuit of said motor, electromagnetic mechanism adapted to gradually remove said resistance from circuit, and electromagnetic mechanism actuated by said slow-acting electromagnetic mechanism to render the pump effective after said resistance has been removed from circuit. 55
29. In combination, a fluid pump, an alternating current motor for driving said pump, said motor having primary and secondary circuits, slow-acting electromagnetic mechanism adapted upon energization to control the current in the secondary circuit of the motor, and electromagnetic means for causing the energization of said electromagnetic mechanism upon closure of the primary circuit. 60
